UNITED STATES PATENT OFFICE.

HARRY PIERCE, OF OAKLAND, CALIFORNIA, ASSIGNOR OF ONE-HALF TO FRANK A. BRIGGS, OF OAKLAND, CALIFORNIA.

AUTOMATIC RECORD-CENTERING MECHANISM FOR PLAYER PIANOS.

1,403,625.

Specification of Letters Patent. Patented Jan. 17, 1922.

Application filed January 5, 1918. Serial No. 210,490.

To all whom it may concern:

Be it known that I, HARRY PIERCE, citizen of the United States, residing at Oakland, in the county of Alameda and State of California, have invented certain new and useful Improvements in Automatic Record-Centering Mechanism for Player Pianos, of which the following is a specification.

This invention is an improved automatic record centering mechanism for player pianos adapted to center any record regardless of whether it is shrunken or swollen so that it will at all times track perfectly; and adapted to lock the record spool positively against axial movement on the rewind so that the record may be rewound without tearing its edges.

In this specification and the annexed drawings, I illustrate my invention in the form which I consider the best, but I do not limit my invention to such form because it may be embodied in other forms and it is to be understood that in and by the claims following the description herein I intend to cover this invention in whatever form it may be embodied.

Referring to the drawings:

Figure 1 is a front elevation of player piano tracker box embodying my invention.

Figure 2 is a plan view of the same.

Figure 3 is a plan view of my improved centering device including the regulating pneumatic and valve.

Figure 4 is a side elevation of the centering device including the regulating pneumatic and valve.

Figure 5 is a side view on an enlarged scale of one of the centering triggers.

Figure 6 is a sectional view of the end of one of the pneumatic exhaust tubes.

Figure 7 is a sectional view of a regulating valve for my invention.

Figure 8 is a sectional view of the regulating pneumatic.

Figure 9 is a transverse sectional view of the regulating pneumatic.

Figure 10 is a side view of the same, illustrating the locking means.

In the drawing 1 indicates a player piano tracker box including a frame 2 in which is mounted the tracker bar 3 and in which are journaled the record winding spool 4 and the spindles 5 and 6 for holding the record spool 7. On the winding spool shaft 8 is secured a gear 9 adapted to mesh

with a pinion 10 slidably keyed on a shaft 11 suitably journaled in bearing 12 in the player piano. On the end of the shaft 11 is secured a sprocket 13 over which travels a chain 14 which also travels over a sprocket 15 on a shaft 16 driven by a suitable motor (not shown). On the shaft 11 is loosely mounted a sprocket 17 and a sprocket 18 is secured on the spindle 5, over which sprockets travels a chain 19. A lever 20, pivoted on a bracket on the tracker box frame 2, actuates the pinion 10 and a clutch 21 whereby the pinion is shifted into and out of engagement with the gear 9 and the sprocket 17 is clutched to the shaft 11 and unclutched therefrom. When the pinion 10 is shifted into mesh with gear 9 the record winding spool is rotated, by the motor, through the medium of shaft 16, sprocket 15, chain 14, sprocket 13, shaft 11, pinion 10, gear 9 and shaft 8, to wind up the record on the spool across the tracker board, and the sprocket 17 is unclutched from the shaft 11 to prevent operation of the record spool 7, through the medium of said sprocket, chain 19 and sprocket 18, and to allow the spool 7 to rotate freely to allow the record to be unwound therefrom across the tracker-board and wound upon the spool 4. On the tracker board 3 are pivoted a pair of valve carrying levers 25 and 26 on which are pivoted respectively a pair of trigger valves 27 and 28, said levers being pivoted in such position that the trigger valves engage the edges of the record 30 as it passes over the tracker board.

The trigger valves 27 and 28 control the ends of tubes 31 and 32 respectively. A pair of regulating pneumatics 33 and 34 are mounted by brackets 35 on the tracker box frame 2. A valve chest 36 is mounted below said pneumatics. The tube 31 leads into the pneumatic 33 and a tube 37 leads from the tube 31 into a chamber 38 in the valve chest 36. The tube 32 leads into a chamber 39 in said valve chest. The chest 36 is also formed with a chamber 40 from which a tube 41 leads to the pneumatic 34. An exhaust tube 45 leads from the reserve (not shown). Said exhaust tube connects with a tube 46, leading into a chamber 47 in chest 36, and with tubes 48 and 49 leading respectively into pneumatics 33 and 34. A port 50 leads from the chest chamber 39 into the chamber 40, which port is con-

trolled by a valve 51. The stem 52 of said valve extends through the wall between the chambers 40 and 47 into the chamber 47 and has a head 53 on its extremity for engaging 5 a pouch 54 forming the dividing wall between the chambers 47 and 38.

A pouch 55 extends across the opening in the wall between the chambers 40 and 47 through which the valve stem 52 extends 10 and is secured tightly around said valve stem, said pouch preventing leakage from one chamber to the other through said opening. To the movable member of the pneumatic 33 is connected one end of rod 60, 15 the other end of which rod is connected to one end of a lever 61 pivoted on a bracket 62 secured to the tracker box frame 2. The other end of said lever 61 is forked and engages a grooved head 5* on the extremity 20 of spindle 5. A spring 63 is connected at its respective ends to the extremity of the spindle 6 and to the frame 2 and tends to draw the spindles 6 and 5 and the record spool 7 to the right.

25 A rod 65 is connected at one end to the movable member of pneumatic 34 and at its other end to a lever 66 pivoted at 67 to the tracker board 3. A link 68 connects the trigger valve lever 25 and the lever 66. A link 30 69 connects the trigger valve lever 26 and the lever 66. The links 68 and 69 are connected to the lever 66 at opposite sides of the pivot 67 of lever 66. A spring 70 connects to the lever 66 and to the frame 2 and tends 35 to swing the lever 66 so as to swing the ends of the trigger valves 27 and 28 away from the edges of the record 30. The ends of the tubes 48 and 49 which lead into the pneumatics 33 and 34 are provided with 40 small vents 75 which establish communication between said tubes and the respective pneumatics into which they lead.

45 In the partition wall 80 between the pneumatics 33 and 34 within a recess 81 in said wall is mounted a lock pneumatic 85 which communicates through tube 86 with exhaust tube 48. A pawl 87 is connected to the movable member of the lock pneumatic 85 and extends through a slot in the wall 80 50 for engaging a ratchet 90 pivoted to the movable member of the pneumatic 33. Said ratchet is provided with a slot 91 into which projects a pin 92 secured in the wall 80, said pin and slot maintaining said ratchet in engaging position for the pawl 87. A bleed hole 100 leads from vacuum chamber 47 to air chamber 38.

55 The operation of my invention is as follows:

60 The edges of the record 30 pass over the tracker board 3 between the trigger valves 27 and 28. Under perfect operating conditions of the record, its edges engage the trigger valves 27 and 28 and open them slightly. A small amount of air is admitted

by valve 27 through tube 31 into pneumatic 33 and through tubes 31 and 37 into the chest chamber 38. The air admitted into said chamber raises pouch 54 slightly and opens valve 51 slightly. A small amount of air is admitted by valve 28 through tube 32 into chest chamber 39, through port 50 into chamber 40, through tube 41 into pneumatic 34. The air thus admitted into pneumatics 33 and 34 is exhausted from said pneumatics as fast as it enters through the vents 75 and a pneumatic balance is established in said pneumatics. If the record shifts to the right the trigger valve 27 closes and the trigger valve 28 opens further, 80 under which conditions both pneumatics 33 and 34 begin to collapse, the air being shut off from pneumatic 34 by the closing of valve 51, and the opening of trigger valve 28 having no effect. The rod 60 is moved to the right by the pneumatic 33 and the record 30 is shifted to the left through the medium of lever 61 and spindle 5, while at the same time the engaging ends of the trigger valves 27 and 28 are swung towards each other through the medium of rod 65, lever 66 and rods 68 and 69, and the edges of the record engage and open both trigger valves 27 and 28. As the trigger valves are thus opened and the record shifts to the left back 90 into alignment with the tracker board, air enters and expands the pneumatics 33 and 34; the air entering pneumatic 33 through tube 31 and the air entering pneumatic 34 through tube 32, chamber 39, port 50, chamber 40 and tube 41, the valve 51 being opened by the air passing from tube 31 through tube 37, into the chamber 38. The expanding of the pneumatics 34 allows spring 70 to swing the engaging ends of the trigger valves away from each other through the medium of lever 66 and links 68 and 69, whereby the trigger valves are brought to their normal position and the record back into alignment with the tracker board, and the pneumatic balance is re-established in the pneumatics 33 and 34.

55 If the record shifts to the left, the trigger valve 27 opens wider and the trigger valve 28 closes, under which conditions 115 pneumatic 33 expands and pneumatic 34 collapses, whereupon the record is shifted to the right by spring 63 and at the same time both trigger valves are swung towards each other through the medium of rod 65, lever 66, and rods 68 and 69 and the trigger valve 28 is engaged and opened by the edge of the record, the trigger valve 27 also being held open by the edge of the record. Air then enters pneumatic 34 through tube 32, chamber 39, port 50 (the valve 51 being open by the air admitted through open trigger valve 27, tubes 31 and 37 into chamber 38) chamber 40 and tube 41, and the spring 70 swings the trigger valves away from each other 130

through the medium of lever 66 and links 68 and 69 and said trigger valves are brought to their normal position, (the pneumatic balance being established in pneumatics 33 and 34) and the record is brought back into alignment with the tracker board. While the player is being played the lock pneumatic 85 is collapsed through tubes 86, 48 and 45 and the pawl 87 is maintained out 10 of engagement with ratchet 90, unlocking the pneumatic 33.

Applicant's double trigger mechanism maintains the lateral shifting movement of the record within a smaller limit, than is 15 possible with other devices, and provides a centering mechanism of highest accuracy and efficiency.

When the record has been played and the player set to rewind the record on the spool 20 7, the reserve is shut off and air enters the lock pneumatic 85 through tube 86 from tube 48 and expands said pneumatic causing pawl 87 to engage ratchet 90 and lock the pneumatic against opening movement and the 25 spool 7 against axial movement, thus preventing tearing of the edges of the record on the rewind.

The air is exhausted from the pneumatics 33 and 34 through small vents 75 and are 30 balanced when the triggers are opened enough to admit atmospheric pressure to the same amount being exhausted. If the trigger valves are opened to a greater extent they will admit more atmospheric pressure 35 than the small vents are exhausting and the opposing springs 63 and 70 will move the pneumatics in the opposite direction or expand them.

Trigger 27 when open admits air direct to 40 pneumatic 33 also to chamber 38 under membrane 54, which lifts valve 51 allowing a direct passage from trigger 28 to pneumatic 34 through chamber 39, port 50, chamber 40 and tube 41.

When trigger 28 is open it will admit air 45 to pneumatic 34, if valve 51 is also open. If valve 51 is not open the trigger 28 has no effect on pneumatic 34, as no air can pass through valve 51 until trigger 27 is open. When this occurs the trigger 28 will 50 balance pneumatic 34. Whenever and however the trigger 27 touches the left edge and the trigger 28 touches the right edge, the web will be perfectly centered regardless of 55 swelling and shrinking. The trigger 27 will hold valve 51 open and balance pneumatic 33, holding music spool in perfect alignment.

The edges of the web control the triggers in a central position regardless of 60 width and the triggers control the web in perfect alignment.

The defect of certain centering devices 65 now in use is that when the edge of the record is shrunken the trigger valve does not

engage it and the record may shift out of alignment without operating the valve to shift it back into alignment, or when the edge of the record is swollen it engages and opens the valve while the record is in alignment and shifts the record out of alignment. 70

This defect is overcome by my invention in the operation of the trigger valve 28, which swings the trigger valve 27 outwardly to prevent the swollen edge from 75 opening said valve and shifting the record out of alignment, and swings the trigger 27 inwardly into contact with the shrunken edge of the record so that said edge will engage the trigger valve 27 immediately and 80 prevent the record shifting to the left out of alignment.

Having described my invention I claim as new and desire to secure by Letters Patent:

1. In a centering mechanism for a player 85 piano, a pair of pneumatics, a pair of trigger valves for engaging the respective edges of the player record and for controlling the admission of air, respectively into said respective pneumatics, means interposed between said trigger valves whereby one of said trigger valves controls the function of the other valve, means operated by one of said pneumatics for shifting the record in one direction, means for shifting 90 the record in the other direction, means operated by the other pneumatic for swinging the trigger valves toward each other into engagement with the edges of the record, means for swinging said trigger valves away 95 from each other to permit centering of the record, and exhaust tubes leading from said pneumatics.

2. In a centering mechanism for a player 105 piano, a pair of pneumatics, a pair of trigger valves for engaging the edges of the record and for controlling said pneumatics, said valves being pivotally mounted, a valve for controlling the function of one of said trigger valves, the other trigger valve controlling said valve, means operated by one 110 of said pneumatics for shifting the record in one direction, means for shifting the record in the other direction, a rod connected to the other pneumatic, a lever connected to 115 said rod, a pair of links connected to said lever and to the respective trigger valves, said trigger valves being swung toward each other by said pneumatic through said rod, lever and links, means for swinging 120 said trigger levers away from each other and exhaust tubes leading from said pneumatics.

3. In a centering mechanism for a player 125 piano, a pair of pneumatics, a pair of trigger valves for engaging the respective edges of the player record and for controlling the admission of air respectively into said respective pneumatics, means interposed between said trigger valves whereby one of 130

- said trigger valves controls the function of the other valve, means operated by one of said pneumatics for shifting the record in one direction, means for shifting the record in the other direction, means operated by the other pneumatic for swinging the trigger valves toward each other into engagement with the edges of the record, means for swinging said trigger valves away from each other to permit centering of the record, an exhaust for each of said pneumatics, and means for locking the record spool against axial movement on the rewind.
- 15 4. In a centering mechanism for player pianos, a pneumatic for shifting the record with relation to the tracker bar, means for engaging one edge of the record when shifted out of registration with the tracker bar for admitting air into said pneumatic to operate said pneumatic to shift the record back into registration with the tracker
- 5 bar, means for automatically adjusting said edge engaging means into operative relation to the edge of the record at all times, and 25 means for automatically locking said pneumatic against operation upon rewinding the record.
5. In a centering mechanism for a player piano, a pair of valve levers, a pair of trigger valves, mounted on said levers for engaging the edges of the record, a lever, a pair of rods connected to said lever respectively at opposite sides of its pivot, and respectively to said valve levers, means controlled by one of said trigger valves for shifting the record into alignment and means for operating said lever controlled by both trigger valves for maintaining the first trigger valve in engagement with the 35 edge of the record at all times.

In testimony whereof I affix my signature.

HARRY PIERCE.
